UNITED STATES PATENT OFFICE

2,276,836

HYDRAULIC OPERATOR

Ernest F. Goetz, Schenectady, N. Y., assignor to
 General Electric Company, a corporation of
 New York

Application February 9, 1940, Serial No. 318,065

6 Claims. (Cl. 60—52)

This invention relates to hydraulic operating mechanism, more particularly to hydraulic operating mechanism in which a centrifugal impeller type pump arranged within a cylinder containing a liquid is utilized to develop a differential in fluid pressure on opposite sides of a piston movably mounted within the cylinder to effect a movement thereof, and it has for an object the provision of a simple, reliable, and improved device of this character.

More specifically, the invention relates to hydraulic mechanism in which the piston is caused to move in an upward direction in response to fluid pressure when the pump is energized and in which the piston is returned to its initial position by the force of gravity or other means when the pump is deenergized, and a further object of the invention is the provision of means for controlling the discharge passage between the discharge of the pump and the lower side of the piston to control the speed of the upstroke of the piston.

A still further object of the invention is the provision of a bypass from the lower side of the piston to the upper side which is controlled by the same means which controls the discharge passage, thereby to control the time of the return stroke of the piston.

In carrying the invention into effect in one form thereof, a piston is movably mounted in a cylinder which contains a liquid, and a centrifugal pump is provided for developing a fluid pressure to effect movement of the piston. The pump housing is provided with an intake passage communicating with the space on one side of the piston and with a circular discharge port or passage communicating with the space on the other side of the piston. A valve sleeve is provided in the discharge passage. This valve sleeve is arranged to close the discharge passage and to open the bypass to provide for rapid return of the piston when the pump is deenergized. In addition, means are provided for adjustably limiting the movement of the valve sleeve which opens the discharge passage and for adjustably limiting the movement of this valve sleeve which opens the bypass, thereby to control the speed of the upstroke and the speed of the downstroke of the piston.

For a better and more complete understanding of the invention, reference should now be had to the following specification and to the accompanying drawing in which Fig. 1 is an elevation partly in section with certain parts of the operating mechanism in one limiting position, Fig. 2 is a

broken view in elevation partly in section with the parts of the operating mechanism in the opposite limiting position; and Figs. 3 and 4 are details.

Referring now to the drawing, a cylindrical liquid container 10 is provided with a cover plate 11 upon which an electric motor 12 is vertically mounted. The cover plate 11 is constructed to provide an integral supporting platform 13 a short distance beneath the top of the container 10. The cylinder and cover plate may be made of any suitable material such as cast iron.

The cylinder 10 is filled with a suitable fluid medium such, for example, as oil, to a point substantially level with platform 13. A piston 14 is arranged within the cylinder 10 for vertical movement, and this vertical movement is transmitted to an external load by means of a pair of connecting rods 15 and 16. The lower ends of these connecting rods are secured by suitable fastening means 17 to the piston 14, and the upper ends of these connecting rods extend through the cover plate 11 and are secured to a crosshead 18 which is adapted to be connected to a suitable load. Near the bottom of the container is an impeller type pump illustrated as comprising a housing 19 having an outer cup-shaped member 19a and an inner member 19b. The housing is provided with a circular discharge passage 20. The portions 19 and 19a of the housing are constructed and arranged to provide a chamber 21 within which a centrifugal impeller 22 is mounted for rotation. This impeller is provided with a central intake passage 23.

As shown, the pump housing members 19b and 19a are secured by means of suitable fastening means 24, 25 to an impeller housing adapter 26 which, in turn, is secured by fastening means 27 to the lower extremity of a tubular member 28, the upper extremity of which is secured to the platform 13 by suitable fastening means. Openings 30, spaced apart in the wall of the tubular member 28 are provided to provide communication from the space above the piston 14 to the intake passage 23 of the pump. It is clear that the wall of the tubular member 28 serve as a partition means and thus confine the discharge of the pump to the space beneath the piston.

A vertical drive shaft 31 is rotatably mounted 50 in a bearing 32 in platform 13 and in a double sealed bearing 33 which is centrally mounted in the lower portion 19a of the pump housing. This drive shaft 31 is connected to the motor shaft 34 by suitable coupling means 35 so that rotation of the motor produces rotation of the impeller 22.

For the purpose of controlling the speed of the up- and downstrokes of the piston, a valve sleeve 36 is slidably mounted in the circular discharge passage 20. The sleeve is provided with rib members 37 which are secured by suitable fastening means illustrated as studs 38, 39 to a yoke 40. A cover pipe 41 surrounds the shaft 31 and is secured to the platform 13 by means of a flange 42 which is bolted or otherwise secured to platform 13. Yoke 40 has a central portion 40a which is bored out and is slidably mounted on the cover pipe 41.

The cover pipe 41 is provided with a shoulder 41a against which a steel ring 43 bears. Cross-piece 37 of the valve sleeve 36 is provided with a circular raised portion 37a which provides a recess for the end of a spring 45.

A lever member 46, which comprises two side arms 46a and 46b and a plate 46c connecting the two arms, is pivoted to two depending lugs 47 and 48 which are formed integral with platform 13. Lever mechanism 46 is provided with pins 46d which slide in slots 49 and 50 in the central portion 40a of yoke 40 and thus provide for movement of lever 46 about its pivots in response to movement of the valve sleeve 36.

For the purpose of adjustably limiting the upward and downward movements of the valve sleeve 36, a pair of adjusting screws 51, 52 are provided which pass through the cover plate 11 and extend to positions in which they cooperate with the lever mechanism 46. Screw 52 may be screwed to a desired position above the connecting plate 46c of the lever mechanism 46 in which it limits the downward movement of valve sleeve 36. The connecting plate 46c is cut away to provide a passage 53 through which adjusting screw 51 extends. Screw 51 may be screwed to a desired position below the connecting plate 46c so that the upward movement of the valve sleeve 36 may be limited as desired when the lever mechanism comes in contact with the nut 54 on the lower end of screw 51. The speed of the upward stroke of the piston 14 will of course depend upon the amount of opening of discharge passage 20 provided by the upward movement of valve sleeve 36. Thus it will be seen that by adjusting the screw 51, the opening of the discharge passage 20 from the pump can be varied and thereby the time required for the upstroke of the piston varied as desired.

The upper circular edge of pump housing member 19b is separated from the lower edge of the housing adapter 26, and thus provided for a bypass from one side of the piston to the other which is independent of the passage through the impeller chamber of the pump. When the upper edge of valve sleeve 36 is below the lower edge of housing adapter 26, the bypass is open, as shown in Fig. 1, and when the valve sleeve 36 overlaps the lower edge of adapter 26, as illustrated in Fig. 2, the bypass is closed. The speed of the downstroke of the piston 14 and therefore the time required for the stroke to be completed will depend upon the amount of opening of the bypass, i. e., the amount of opening between the lower edge of housing adapter 26 and the upper edge of valve sleeve 36. Thus it will be seen that by varying the adjustment of screw 52, the opening of the bypass can be varied and thereby the time required for the downstroke of the piston can be varied as desired. The container 10 is filled with a liquid, such as oil, up to the level of platform 13. Assuming that the screw 52 is adjusted to provide maximum opening of the

bypass, the valve sleeve 36 will be in the position illustrated in Fig. 1.

With the foregoing understanding of the elements and their organization, the operation of the device itself will readily be understood from the following detailed description.

Energization of the motor 12 by connection with a source of electric power produces a rotation of the impeller drive shaft 31 and the pump impeller 22. Oil is drawn from the space beneath the piston 14 through the bypass between the valve sleeve 36 and housing adapter 26 and into the central intake passage 23 of the pump. Oil is also directed into the intake passage 23 by the tubular member 28. This oil is drawn from the space above the piston 14 through the openings 30, down through the tubular member and into the centrally disposed intake passage 23. The impeller forces the oil radially outward through the impeller chamber and through orifices in housing member 19b into the circular discharge passage 20, as a result of which a fluid pressure is produced against the lower surface of valve sleeve 36 of sufficient magnitude to raise the valve sleeve 36 to a position in which the lower edge of the valve sleeve is above the upper edge of housing member 19a.

The loading of spring 45 is such that the impeller must come up to full speed and develop a predetermined oil pressure in order to move the valve sleeve and thereby open the discharge passage from the pump housing and close the bypass. Thus this part of the operating cycle, i. e., the starting time for movement of the piston is independent of the external load on the piston and is therefore uniform for all loads.

After the discharge passage opens (the bypass being now closed), there is developed across the piston a pressure differential, i. e., a difference in fluid pressure on opposite sides of the piston. This pressure differential causes the valve sleeve 36 to move to an intermediate position in which the opening of the discharge passage and the fluid pressure differential across the piston is dependent upon the external load. That is to say, when the external load is heavy, the valve sleeve will be in a position to produce a correspondingly large opening of the discharge passage, and when the external load is light, the valve sleeve will be in a position in which the opening of the discharge passage is correspondingly small. In other words, the pressure for moving the piston is roughly proportional to the external load on the piston, and thus the time required for the upstroke is substantially uniform for a wide range of loads.

As soon as the piston has completed its stroke, the oil pressure will reach its maximum and the valve sleeve 36 will complete its travel to the limit imposed by the adjustment screw 51 as illustrated in Fig. 2.

The return stroke is initiated in response to deenergization of the motor. As a result of this the impeller slows down, and the oil pressure differential decreases rapidly. When the oil pressure decreases but a slight amount, the spring 45 forces the valve sleeve down thus shutting off the oil flow through the impeller chamber and the discharge passage, and opening the bypass so that oil flows from the space beneath the piston through the bypass into the tubular member 28 and out through the openings 30 into the space above the piston. It will be noted that the time required for the piston to start down is independent of the external load. The downstroke

is accomplished by allowing the oil beneath the piston to rush through the bypass. This results in a very quick return stroke. The time required for the downstroke varies slightly with the load, but the downstroke is accomplished so rapidly that for all practical purposes of operation, the time may be considered to be substantially uniform.

Although in accordance with the provisions of the patent statutes this invention is described as embodied in concrete form, and the principle thereof is described together with the best mode in which it is now contemplated applying that principle, it will be understood that the elements and arrangements shown and described are merely illustrative and that the invention is not limited thereto, since alterations and modifications will readily suggest themselves to persons skilled in the art without departing from the true spirit of this invention or from the scope of the annexed claims.

What I claim as new and desire to secure by Letters Patent of the United States is:

1. An hydraulic operating mechanism comprising in combination, a fluid container, a piston mounted in said container for relative movement with respect thereto, an impeller housing mounted in said container having an impeller chamber, an annular shaped discharge passage surrounding said chamber and leading from said chamber to the space on one side of said piston, and an intake passage in said housing leading toward the space on the other side of said piston, conduit means leading from the space on said other side of said piston into the space on said one side and having its open end on said one side spaced from said intake passage in said housing to provide a bypass from said conduit means around said housing to said space on said one side of said piston, an impeller rotatably mounted in said chamber for producing a differential fluid pressure for moving said piston, and a valve sleeve in said discharge passage movable in response to pressure produced by rotation of said impeller to provide a confined communication from said intake passage in said housing to said open end of said conduit means, close said bypass and open said discharge passage thereby to apply a differential pressure to said piston to effect movement thereof, and biasing means for moving said sleeve to open said bypass and close said discharge to effect quick return of said piston in response to deenergization of said impeller.

2. An hydraulic operating device comprising in combination, a fluid container, a piston movably mounted therein, an impeller housing having an impeller chamber, an intake passage leading from said chamber to the space on one side of said piston and a discharge passage leading from said chamber to the space on the opposite side of said piston, an impeller in said chamber, means for driving said impeller thereby to produce a differential fluid pressure on said piston for effecting movement thereof, means providing a quick release passage from one side of said piston to the other independent of the passage through said impeller chamber, a valve sleeve arranged in said discharge passage, means biasing said valve sleeve to cut off said discharge passage, said sleeve being movable in response to energization of said driving means to open said discharge passage and to close said quick release passage and said biasing means serving to move said valve sleeve to open said quick release passage and to close said discharge passage

5 in response to deenergization of said driving means, and adjusting means for limiting the movement of said sleeve to open said discharge passage thereby to control the time of movement of the piston in one direction.

3. An hydraulic operating device comprising in combination, a fluid container, a piston movably mounted therein, an impeller housing having an impeller chamber, an intake passage leading from said chamber to the space on one side of said piston and a discharge passage leading from said chamber to the space on the opposite side of said piston, an impeller in said chamber, means for driving said impeller thereby to produce a differential fluid pressure on said piston for effecting movement thereof, means providing a quick release passage from one side of said piston to the other independent of the passage through said impeller chamber, a valve sleeve arranged in said discharge passage, means biasing said valve sleeve to cut off said discharge passage, said sleeve being movable in response to energization of said driving means to open said discharge passage and to close said quick release passage and said biasing means serving to move said valve sleeve to open said quick release passage and to close said discharge passage in response to deenergization of said driving means, and adjusting means for variably limiting the movements of said sleeve to open said quick release passage and to open said discharge passage to control the time of the work and return strokes of said piston.

4. An hydraulic operating device comprising in combination, a fluid container, a piston mounted for movement in said container, an impeller housing mounted within said container and immersed in the fluid therein, said housing being provided with an impeller chamber, an intake passage leading from said chamber to the space above the piston and a discharge passage leading from said chamber to the space beneath the piston, means providing a quick release passage from the space beneath said piston to the space above said piston independent of the passage through said impeller chamber, an impeller within said housing and means for driving said impeller to produce a differential fluid pressure on said piston for effecting movement thereof, a valve sleeve arranged in said discharge passage so as to be responsive to energization of said impeller to open said discharge passage and close said quick return passage, biasing means for actuating said sleeve to open said quick return passage and close said discharge passage in response to deenergization of said impeller, and means for adjustably limiting the movements of said sleeve to open said discharge passage and to open said quick return passage thereby to control the time of the up- and downstrokes of said piston.

5. An hydraulic operating mechanism comprising in combination, a fluid container, a piston movably mounted therein, an impeller housing mounted in said container immersed in the fluid contained therein and having an impeller chamber, a discharge passage leading from said impeller chamber to the space on one side of said piston and an intake passage leading from said chamber toward the other side of said piston, a tubular member disposed within said container passing through said piston and providing a passage from the space on said other side of said piston to said intake passage, an impeller rotatably mounted in said chamber for producing

a differential fluid pressure for moving said piston, means providing a bypass from said tubular member about said impeller chamber to said first mentioned space on said first mentioned side of said piston, a valve sleeve in said discharge passage responsive to pressure due to the rotation of said impeller to open said discharge passage and close said bypass thereby to apply a differential pressure to said piston to effect movement thereof, and biasing means for moving said sleeve to open said by-pass and close said discharge to effect quick return of said piston in response to deenergization of said impeller.

6. An hydraulic operating mechanism comprising in combination, a fluid container, a piston movably mounted therein and having a rod extending through said container for connection with a load, an impeller housing mounted in said container immersed in the fluid therein, and having an impeller chamber, said housing having a central inlet and a circular discharge passage leading from said chamber to the space on one side of said piston, a tubular member extending from said inlet through said piston to provide an intake passage leading to the space on the

other side of said piston, an impeller in said impeller housing, means for driving said impeller comprising a drive shaft extending through said tubular member to said impeller, a valve sleeve in said discharge passage, a spring surrounding said drive shaft biasing said valve sleeve to close said discharge passage, a bypass leading from one side of said piston to the other independently of the passage through said impeller chamber, said impeller serving when rotated to produce a fluid pressure to move said sleeve to open said discharge passage and close said bypass and to produce a differential fluid pressure on opposite sides of said piston to effect movement thereof, said differential pressure being proportional to the load on said piston so that the opening of said discharge passage is also proportional to the load on said piston and the time for the complete upstroke of the piston is substantially the same for a wide range of piston loads, said biasing spring serving to return said valve sleeve to its closed position thereby to open said bypass to effect quick return of said piston upon a drop in pressure due to the stopping of said impeller.

ERNEST F. GOETZ.
